(57) **CLAIM**

The ornamental design for a trivet, as shown and described.

DESCRIPTION

FIG. 1 is a perspective view of a trivet showing my new design.

FIG. 2 is a front view thereof, a rear view being a mirror image.

FIG. 3 is a left side view thereof.

FIG. 4 is a right side view thereof.

FIG. 5 is a top view thereof; and,

FIG. 6 is a bottom view thereof.

The broken lines show portions of the design that form no part of the claimed design.

1 Claim, 4 Drawing Sheets
